UNITED STATES PATENT OFFICE.

WILLIAM F. MAHONY, OF WASHINGTON, DISTRICT OF COLUMBIA.

EYESHADE.

Application filed March 19, 1923. Serial No. 626,160.

This invention relates to eye-shades or shields, and more particularly to the provision of means whereby an eye-shade may be folded into a very compact space so as to be conveniently carried in one's pocket or transmitted through the mails in a small sized envelope without being injured thereby.

One of the essential features of the present development resides in the provision of a foldable eye-shade composed of diaphanous or some other semi-transparent material, so constructed as to permit the wearer to have an uninterrupted range of vision.

A further object of the invention is to provide an improved eye-shade, the body portion or vizor of which may be formed of either a single piece of material or of separate sections secured together in such a manner as to form an eye-shade which may be compactly folded without danger of being cracked or broken.

In the drawings,

Figure 1 is a plan view of one embodiment of my invention.

Figure 2 discloses a side view of the eye-shade shown in Figure 1 applied to the head of the wearer.

Figure 3 shows the eye-shade illustrated in Figure 1 in folded position, and in which position it may be placed in an envelope as shown in dotted lines in this figure.

Figure 4 shows a modified form of the invention applied to the head of a wearer.

Figure 5 is a side elevational view of Figure 4.

Figure 6 is a plan reverse view of the eye-shade in Figure 4.

Figure 7 is a fragmentary sectional view of the securing means shown in Figure 6.

Figures 8, 10 and 11 are plan views somewhat similar to Figure 1 but illustrating different forms of head straps.

Figure 9 is a perspective view of a tab or strip comprising a portion of the head strap shown in Figure 8.

Figure 12 shows the eye-shade illustrated in Figure 11 in folded position.

Referring to the drawings wherein like numerals indicate like parts in the various views, 10 denotes the body portion or vizor of the eye-shade, which may be formed of any suitable material. Preferably, the eye-shade is composed of diaphanous material, such as celluloid or the like.

55 The eye-shade 10 may be cut or stamped from a single strip of material, as shown in

Figure 1. In order to facilitate the stamping operation and to eliminate the waste of the material used, the inner and outer edges of the eye-shade are of substantially the same curvature. The ends of the eye-shade are provided with ears or projections 11, to which a head strap is adapted to be connected in any desired manner. It will be observed, as indicated by the dotted lines 60 in Figure 1 that the outer extremities of the ears 11 are substantially in alignment with the edges of the body portion of the vizor, so that when the shade is applied, it will completely shield the eyes and prevent light 65 from entering at the side sections. Additionally, in order that the shade may comfortably fit the ear of the wearer, a cut-away portion 12 is formed in the outer edges of the vizor, which snugly engages the upper 70 part of the ear, as shown in Figure 2.

In Figures 1, 2 and 3, the vizor 10 of the eye-shade is shown provided with the creases 13 which divide the shade into a central portion 14 and end portions 15, the end portions being substantially of the same length as the central portion, and adapted to be folded thereover. The line of the creases 13 preferably converge toward the center of curvature of the edges of the vizor so that when folded the end portions 15 will lie substantially within the bounds of the central portion 14, as shown in Figure 3. The creases 13 are preferably positioned to one side of the line of vision of the eye so as not to obstruct the view of the wearer.

The vizor 10 when made of celluloid or other easily frangible material is preferably heated during the creasing operation so as to prevent the sides 15 from cracking when brought into the folded position.

Any suitable means for securing the eye-shade to the head may be employed. I have conventionally shown in Figure 1 that this means comprising a cord 16 secured at one end to an opening in the ear 11 by means of an eyelet 17. The end of the cord 16 is inserted through the hole in the ear 11, and secured therein by the eyelet 17, which is adapted to fit in said opening. The cord 16 passes in one direction through an opening 18, and in the opposite direction through a larger eyelet 19 formed in the plate 20. The cord is threaded through an eyelet 21 at the opposite end of the vizor of the eye-shade, and is then secured to the larger opening in the plate 20 by the eyelet 19. This

2
form of head strap will permit of ready adjustment of the eye-shade upon the head, it being merely necessary to move the plate 20 back and forth upon the cord until the preferred adjustment is secured, and then, by reason of the friction between the cord and the edges of the openings 18 and 19 in the plate 20, the cord or head band 16 will remain in adjusted position. By reason of the 10 ears 11 it will be seen that the head straps 16 may be shortened to a greater degree than if the ears 11 were not provided.

Referring to Figures 4, 5 and 6, wherein is disclosed a modified form of the invention, which differs from the form previously described, in that the eye-shade 10' is composed of the central section 14' and the separate end sections 15' which are secured to the adjacent edges of the central section by 20 any suitable means, such as the straps or bands 13'.

In order to secure the separate sections of the eye-shade together when the latter is made of celluloid, it has been found that an 25 effective adhesive is provided by making the straps 13' preferably of silk material, which, before being placed in position, is immersed in a suitable chemical, ether, for example, so as to be completely saturated. The straps 30 are then applied to the adjacent edges of the sections that are to be connected. The parts are then allowed to set so that when the operation is completed the silk will adhere to the celluloid in such a manner as to provide 35 an effective connecting means and permit the sections to be folded without danger of the straps becoming loose.

In Figure 8, I have shown a slightly different form of head band. In this embodiment, the head band comprises a cord 22 secured at one end by means of the eyelet 17 to the ear 11 and at the other end to a strip or tab 23 having a number of spaced perforations or apertures 24. The tab 23 is secured in adjusted position to the ear 11 by 45 means of a fastener 25 which may be of any suitable construction. As shown in Figure 9, the tab 23 is formed by bending the material of which it is formed over upon itself 50 and then striking up one of the edges so as to provide a flange 26 which reinforces the tab.

In each of the embodiments of my in-

vention shown in Figures 10, 11 and 12, the head band comprises a plurality of sections of flat strips, in the present instance three such sections 27 being illustrated. The sections 27 are secured together and the ends of the bands are secured to the ears 11 of the vizor by means of the fasteners 25. One or all of the strips 27 may be provided with a plurality of spaced perforations 28 so as to permit the length of the strap to be adjusted to fit the head of the particular person to wear the eye-shade. In Figure 10, I have shown two of the sections 27 provided with a plurality of perforations 28.

It is preferable to provide both ends of each of the strips 27 with a plurality of perforations 24, as shown in Figures 11 and 12. With this latter arrangement the length of the head band may be adjusted to fit the head of the wearer, and at the same time the adjustment may be such that the head band may be folded to lie within the area of the folded body portion of the eye-shade. In Figure 12, the eye-shade is shown in folded condition, and in this position the end sections of the head band cross each other and the central section extends longitudinally of the vizor.

It is to be understood that such changes that involve mere mechanical skill may be made to my invention without departing from the spirit thereof and the scope of the appended claim.

I claim:

An eye shade comprising a curved central section, curved end sections movably connected to said central section, said sections having their inner and outer edges of substantially the same curvature and the end sections adapted when folded to lie wholly within the central section, the outer extremities of the end sections having cut away portions forming lateral projections, said projections being arranged relative to the edges of the end sections so that the projections will snugly fit the ears of the wearer and prevent light from entering through the end sections, and an adjustable head strap connected to said projections.

In testimony whereof I have hereunto set my hand.

WILLIAM F. MAHONY.
